UNITED STATES PATENT OFFICE.

THOMAS HENRY NAUGHTON, OF PHILADELPHIA, PENNSYLVANIA.

APPARATUS FOR RECOVERING WASTE ALCOHOL FROM LIQUOR CASKS AND BARRELS.

No. 892,006.

Specification of Letters Patent.

Patented June 30, 1908.

Application filed November 23, 1907. Serial No. 403,499.

To all whom it may concern:

Be it known that I, THOMAS HENRY NAUGHTON, a citizen of the United States, residing in Philadelphia, in the county of Philadelphia and State of Pennsylvania, have invented new and useful Improvements in Apparatus for Recovering Waste Alcohol from Liquor Casks and Barrels, of which the following is a specification.

10 This apparatus has for its object to recover the alcohol remaining in barrels and casks which have contained liquors and wines, after said barrels and casks have been emptied, the alcohol being found mainly in and 15 more or less absorbed by the charred inner surface of the wood of which the barrels are made.

The present invention is intended to be applied to individual barrels, rather than to 20 a series of connected barrels, and to recover the waste alcohol from one barrel after another as it is applied to them in turn.

The invention consists in the novel construction and arrangement of parts herein- 25 after described, and illustrated in the accompanying drawings, the method or process therefor being made the subject of a separate application for Letters Patent of even date herewith.

30 In the drawings, Figure 1 is an elevation of my improved apparatus applied to a barrel which is illustrated as lying on its side, the said barrel and a small portion of the lower end of the apparatus being shown in section, 35 and the apparatus connecting with a suitable condensing tank (broken out in order to show the worm) and a receiving tank shown in elevation. Fig. 2 is an enlarged section in detail of the bung and its cap, the parts connecting with said bung, and extending 40 through it being shown in elevation.

Similar letters of reference indicate corresponding parts.

a represents a liquor or wine barrel or cask 45 which has been emptied of its contents and is lying on its side.

b represents a condensing tank provided with a suitable worm *c*, and *d* is a receiving tank which is connected with the worm by 50 the pipe *e*.

f is a hollow bung, made preferably of wood instead of metal in order to avoid the necessity of a screw-thread, the bung being of the usual conical shape, and *g* is a metallic cap whose annular flange *g'* is bored to receive bolts *h* which screw into a metallic ring

k which is disposed around the conical bung at a short distance below its upper end. Nuts *j* on the bolts serve to force the cap *g* down upon the washer *i* which is between 60 said cap and the upper edge of the hollow bung, the ring *k* being prevented by the expanding shape of the bung from being forced any higher than the point illustrated in the drawings.

m represents a heating pipe or main, closed at its lower end, preferably by means of a stopple *n*, said lower end being adapted to rest on the inner surface of the barrel at its lowest portion as it lies, and the lower portion *m'* of the heating pipe being preferably bent or coiled in order to provide a greater heating surface. This pipe extends up centrally through the tubular bung *f* without coming in contact therewith and thereby 70 burning or injuring it, and through the metallic cover *g*, into which it is screwed. The upper end of the pipe *m* is screwed into the lower end of a pipe *p* which connects with a steam-supply, and is provided with a suitable valve *l*. Near the extreme lower end of the pipe *m* a small pipe *r* connects with its interior and coils at *s* around the pipe *m* and extends from the upper end of such coiled portion through the cap *g* to the waste or 80 discharge-pipe *u*. A pipe *t* has its lower end screwed into the cap *g* whereby it opens into the interior of the bung *f*, said pipe *t* extending to and connecting with the worm *c* in the condensing tank *b*.

In practical operation, I first place water in the barrel, through the bung-hole, in a sufficient quantity to submerge the main heating pipe *m* (including its portion *m'*) to the desired depth. The parts are then applied in the position indicated in the drawings, the coiled portion *m'* of the main heating pipe being submerged, and the bung *f* being driven tightly into position. Steam is then introduced from a suitable boiler 100 through the pipe *p* into the pipe *m*, with the effect of vaporizing the water in the barrel until the vapor completely fills the barrel and comes in contact with all portions of its charred inner surface, thus volatilizing the 105 alcohol contained in such charred portion. This vapor containing the alcohol passes out through the pipe *t* into the coil *c* in the condensing tank *b*, and thence through the pipe *e* into the receiving tank *d*. The inflow of 110 steam through the pipe *m* is regulated by the valve *l* so that its pressure is sufficient to,

drive the water condensing in the lower end of the coiled portion m' into the pipe r and through the coil s therein into the discharge-pipe u , said coil around the main heating pipe operating to aid in heating the interior of the barrel. The water in the barrel is introduced in sufficient quantity to enable the steam heat to completely vaporize the barrel and thus volatilize the alcohol contained in the charred inner surface, said volatilized alcohol passing out with the vapor through the bung and into the pipe t , while the condensed steam passes out through the pipe r . It is evident that there is no loss of steam, the live steam being all utilized, that which passes into the discharge-pipe u being water.

The simplicity of the construction of the apparatus enables it to be easily applied to one barrel after another, its operation being very rapid.

Having thus fully described my invention, what I claim, and desire to secure by Letters Patent is:—

1. In an apparatus for the purpose specified, a hollow bung adapted to be applied to a barrel and open at its lower end, a steam-heating main pipe extending through said bung and adapted to extend toward the lower portion of the barrel and closed at its lower end, a discharge-pipe extending from a point near the extreme lower end of the interior of the heating pipe through the bung, a condensing tank, a receiving tank, a pipe extending from the interior of the bung to the condensing tank, and a pipe connecting the condensing tank and the receiving tank.

2. In an apparatus for the purpose specified, a tubular bung adapted to be applied to a barrel, a cap secured on and closing the upper end of said bung, a steam-heating main pipe extending through said cap and bung and adapted to extend toward the lower portion of the barrel and closed at its lower end, a discharge-pipe extending from a point near the lower end of the interior of the heating pipe through the bung and cap,

a condensing tank, a receiving tank, a pipe extending from the interior of the bung through the cap to the condensing tank, and a pipe connecting the condensing tank and the receiving tank.

3. In an apparatus for the purpose specified, a tubular bung adapted to be applied to a barrel, a cap secured on and closing the upper end of said bung, a steam-heating main pipe extending through said cap and bung and adapted to extend toward the lower portion of the barrel and closed at its lower end, a discharge-pipe extending from a point near the lower end of the interior of the heating pipe and formed into a coil around that portion of the heating pipe which is within the barrel and extending thence through the bung and cap, a condensing tank, a receiving tank, a pipe extending from the interior of the bung through the cap to the condensing tank, and a pipe connecting the condensing tank and the receiving tank.

4. In an apparatus for the purpose specified, a hollow bung adapted to be applied to a barrel and open at its lower end, a steam-heating main pipe extending through said bung and adapted to extend toward the lower portion of the barrel, a condensing tank, a receiving tank, a pipe extending from the interior of the bung to the condensing tank, a pipe connecting the condensing tank and the receiving tank, and a discharge-pipe connected with the lower portion of the steam-heating pipe and extending along in proximity with that portion of the steam-heating pipe which is within the barrel and thence out through the bung.

In testimony whereof I have signed my name to this specification in the presence of two subscribing witnesses.

THOMAS HENRY NAUGHTON.
